UNITED STATES PATENT OFFICE.

WALTER DAVID NIEDERER, OF HAYDEN, ARIZONA.

DESIGN FOR AN ARTICLE OF JEWELRY.

54,448.

Specification for Design.

Patented Feb. 10, 1920.

Application filed December 6, 1918. Serial No. 265,648. Term of patent 14 years.

To all whom it may concern:

Be it known that I, WALTER DAVID NIEDERER, a citizen of Switzerland, residing at Hayden, in the county of Gila and State of Arizona, have invented a new, original, and ornamental Design for an Article of Jewelry, of which the following is a specification, reference being had to the accompanying drawing, forming a part thereof.

The figure is a view of a locket, showing my new design.

I claim:

The ornamental design for an article of jewelry, as shown.

WALTER DAVID NIEDERER.

Witnesses:

F. J. WRIGHT,
T. R. LINGLE.
